UNITED STATES PATENT OFFICE.

EDWIN C. WASHBURN, OF ENGLEWOOD, NEW JERSEY.

FRICITION DRAFT GEAR.

Application filed February 5, 1921. Serial No. 442,658.

To all whom it may concern:

Be it known that I, EDWIN C. WASHBURN, a citizen of the United States, residing at Englewood, in the county of Bergen and 5 State of New Jersey, have invented certain new and useful Improvements in Friction Draft Gears; and I do hereby declare the following to be a full, clear, and exact description of the invention, such as will enable others skilled in the art to which it 10 appertains to make and use the same.

This invention relates to a friction draft gear, particularly to such a device designed for use with railway cars. It is now the 15 practice to equip railway cars of practically all types with some form of spring or friction draft gear to absorb the shock occasioned by starting and stopping the train and to relieve the car structure from strains incident thereto. Many of the friction draft gears in use are of complicated structure requiring many parts and thus resulting in greatly added weight.

It is an object of this invention to provide 20 a friction draft gear of few parts which will be of light weight, inexpensive and yet very efficient for the purposes had in view, and which will be efficient in operation to withstand the maximum strains and shocks usually occurring in railway operation.

It is a further object of the invention to provide a draft gear having a combined friction and spring element, the spring and friction feature of which are successfully 25 brought into operation.

It is also an object of the invention to provide a novel reinforcing means for the enclosing strap or yoke used with the friction draft gear.

These and other objects and advantages 30 of the invention will be apparent from the following description made in connection with the accompanying drawings in which like reference characters refer to the same 35 parts throughout the different views, and in which,

Fig. 1 is a longitudinal section of the draft gear taken on the line 1—1 of Fig. 2;

Fig. 2 is a view in side elevation of the 40 draft gear, as shown in Fig. 1;

Figs. 3 and 4 are partial sectional views similar to Fig. 1, showing the gear in successive stages of compression; and

Fig. 5 is a transverse section taken on the 45 line 5—5 of Fig. 1.

Referring to the drawings, the gear is

shown as enclosed in longitudinal channel members 1 which are suitably secured to the car structure and terminate in the car sills at their forward ends. These members are 50 connected at one end by channel members 2 which form the abutment for a back plate 3^a and the members 1 are also connected by upper and lower channel members 3 forming a supporting means for parts of the draft gear. The channel members 1 are reinforced at the sides by plates 4 having elongated thickened portions or bosses at their central portions through which are formed 55 elongated slots 5. A bar 6^a of oblong or 60 elongated elliptical cross section is secured in the head member 6 and has its ends projecting through the slots 5. The head member 6 abuts at its front end with the end of the coupling head or drawbar member 7 65 and has a terminal projection extending into the rear end of said member 7. The member 7 is formed with a transverse opening 70 in which is secured a bar 8 also of oblong or 75 elongated elliptical shape, and this bar projects at either side of said member and has 80 its ends secured in elongated slots formed in the free ends of an elongated U-shaped strap or yoke member 9. The ends of member 9 receive the bar 8 and are reinforced 85 by members 10 provided at their inner sides with raised portions or bosses surrounding 90 the slot receiving the bar 8, and these members 10 are preferably cast about or on the ends of the yoke member 9 so as to be more 95 or less integrally connected thereto. The yoke member 9 carries at its closed end a buffer plate 11 provided with a central recess or slot extending centrally thereof, 100 which slot is of greater depth than the thickness of the yoke 9 so that the rear surface of the yoke will not come into contact with the plate 3^a. Disposed between the buffer plate 11 and the head member 6 is a volute 105 plate spring 12 comprising several convolutions which are stepped relative to each other, or formed in the shape of a helix. The inner and outer ends of this spring are tapered in thickness, as shown in Fig. 5. Disposed within the inner convolution of the spring 12 are a plurality of blocks 13 having their outer surfaces curved and having their inner surfaces plane and converging at the longitudinal center thereof. In 110 the embodiment of the invention illustrated, eight of these blocks are shown and a pair of oppositely disposed octagonal wedge

members 14 are arranged to have their flat plane surfaces in contact with the enclosed plane surfaces on said blocks. These wedges, as shown in Figs. 1 and 4, are inferiorly cored and are bored to receive a connecting nutted bolt member 15. The head member 6 is provided with a raised central portion at its inner end which is, in turn, provided with a conical raised portion 16 over which the outer wedge member 14 is adapted to fit. The buffer member 11 is provided on its face opposite the spring, with a circular unstanding projection adapted to fit within the inner convolution of the spring.

The operation of the device is as follows: Assuming that a sudden pulling stress is placed upon the coupling head 7, this stress will be transmitted to the yoke member 9 by the bar 8 and through the spring wedges to the bar 6^a, and thence to the members 1 and the car body. The shock occurring owing to the inertia of the car mass, will first be taken by the spring 12 and the yoke member 9 will move relatively to the member 6^a and compress the spring 12 and thus tend to bring all of the convolutions thereof into alinement. When the spring has been sufficiently compressed to take up the space between the buffer members 11 and the adjacent wedge member 14, any further movement will result in the wedge members 14 being pushed together. This will spread the wedge blocks 13 which will engage with the inner convolutions of the spring and begin to expand the spring from the inner side outwardly. If the stress is sufficient the movement will continue until the parts reach the position shown in Fig. 4, the spring 12 being entirely compressed lengthwise and the blocks 13 having opened the spring to the full extent of their movement. It will be noted that the surfaces of the wedge members 14 acting on the inner surface of blocks 13 will exert great friction. This frictional effect will be greatly increased by the friction of the curved surface of the blocks 13 on the inner surface of the spring and the friction will be still further augmented by the friction of the various convolutions of the spring on each other as the spring is expanded. It will thus be seen that the draft gear utilizes the combined spring and friction action of the volute spring 12 as well as the additional friction of the wedge members. When the stress is relieved, the spring 12 will gradually assume its normal shape and will separate the members 6 and 11. When the stress is placed on the car by a sudden movement in the opposite direction, the bar 6^a will travel in the slot 8, the buffer plate 11 contacting with the abutment member 3^a. The device is designed to operate in a compression movement of substantially 2¹/₂

inches, the clearance in the slots in the side member 1 and the drawbar allowing for approximately 2¹/₂ inches of movement which is the distance specified by the Master Car Builders Association.

The projection 16 is formed to engage the outer wedge member 14 so that the same will be prevented from dropping down out of place, the other member 14 being held in position by the spring. It will be noted that by enclosing the end of the yoke member 9 by the buffer plate 11 the back end of the yoke will not be repeatedly pounded against the back plate 3^a, the impact being taken by member 11. This will avoid crystallization of the metal of the yoke and prevent untimely breakage thereof.

From the above description it is seen that applicant has invented a friction draft gear of few and rugged parts which are of comparatively simple construction, the operation of which is positive and certain. The draft gear, as a whole, is quite light and yet the parts are of sufficient strength to sufficiently cope with the maximum stress encountered. In actual tests the device is found to operate very successfully and to successfully handle exceedingly large stresses. The parts are preferably made of steel, although it will be understood that other material may be used if found desirable in practice.

It will, of course, be understood that various changes may be made in the form, details and proportions of the device without departing from the scope of applicant's invention, which, generally stated, consists in the matter shown and described and set forth in the appended claims.

What is claimed is:

1. A draft gear having in combination a longitudinal compressible volute plate spring, means for compressing said spring and frictional radially movable means for expanding the same.
2. A draft gear having in combination a volute plate spring and friction means engaging the inner surface thereof and radially movable for expanding the same.
3. A draft gear having in combination, spaced follower plates, a longitudinally compressible volute plate spring disposed therebetween, oppositely disposed wedge members between said plates, and a plurality of circumferentially arranged wedge blocks having diverging wedge surfaces at each end, respectively, contacting said wedge members and having outer surfaces contacting the inner surfaces of said spring.
4. A draft gear having in combination a volute plate spring, frictional means enclosed thereby for expanding the same, and frictional means engaging said first mentioned frictional means to move the same radially to expand said spring.

5. A draft gear having in combination spaced follower plates, spaced oppositely disposed wedge members contacting said follower plates and adapted to be moved there-
5 by, a series of wedge blocks disposed about said wedge members, and a volute plate spring enclosing said blocks and engaging the entire cylindrical surfaces thereof.
6. A draft gear having in combination spaced follower plates, a longitudinally compressible volute spring disposed between and normally contacting said plates, expansible friction means disposed in said spring between said plates normally spaced
10 from one of the same, whereby, when said plates are moved together, the spring will first be compressed longitudinally and will then be expanded by said friction means being engaged and actuated by said plates.
7. A draft gear having in combination spaced follower plates, a longitudinal compressible volute spring arranged therebetween, oppositely disposed wedge members disposed between said plates and a series
20 of wedge blocks circumferentially arranged about said wedge members enclosed by and frictionally engaging the inner surface of said spring and frictionally engaging the outer surfaces of said wedge members.
8. A draft gear having in combination spaced follower plates, a longitudinal compressible volute spring disposed therebetween, oppositely disposed wedge members also disposed between said plates, means
25 connecting said wedge members, and a series of wedge blocks circumferentially arranged about said wedge members and enclosed by said spring.
9. A draft gear having in combination a volute plate spring, a series of wedge blocks having their outer surfaces arranged with their circumference contacting the inner surface of said spring and having their inner surfaces formed with plane surfaces converging toward the longitudinal center, and oppositely disposed wedge members disposed in said series of wedge blocks and having a plurality of plane surfaces thereon engaging the inner plane surfaces of said wedge blocks.
10. A draft gear having in combination a volute plate spring, and radially movable expanding means contained within the same for expanding said spring and having cylindrical surfaces frictionally engaging substantially the entire inner surface of said spring.
11. A draft gear having in combination a volute plate spring and segmental wedges disposed inside of the convolutions thereof and having surfaces engaging substantially the entire inner surface of said spring for expanding said spring against the tension thereof and the friction of the convolutions, one on the other.

In testimony whereof I affix my signature.

EDWIN C. WASHBURN.
